UNITED STATES PATENT OFFICE.

BUTLER F. GREER, OF SAN FRANCISCO, CALIFORNIA.

BOOK-FORM SAVINGS BANK.

Application filed April 13, 1921. Serial No. 461,154.

To all whom it may concern:

Be it known that I, BUTLER F. GREER, a citizen of the United States, and a resident of the city and county of San Francisco and State of California, have invented a new and useful Book-Form Savings Bank, of which the following is a specification.

My invention relates to small savings banks and the broad object of the invention is to provide a savings bank simulating a book characterized by simple structural elements giving a sturdy construction at low cost. More particularly an object of the invention is the provision of a bank of the character described having an improved cover simulating a binding and improved means for securing the cover to the inner casing of the bank so that if need arises, a new cover may readily be applied.

My invention possesses other objects and features of advantage, some of which, with the foregoing, will be set forth in the following description of my invention. It is to be understood that I do not limit myself to the showing made by the said description, as I may adopt variant forms of my invention within the scope of the claims.

In the drawings, Fig. 1 is a perspective view of my bank. Figs. 2, 3 and 4 are vertical sectional views taken in planes indicated by the lines 2-2, 3-3, and 4-4 respectively, of Fig. 1. Fig. 5 is a perspective view of the metal corner detached. Fig. 6 is a plan view of the bank with portions broken away to show the reenforced end of the back and the coin slot. Fig. 7 is a sectional view taken in the plane indicated by the line 7-7 of Fig. 6. Fig. 8 is a perspective view of the cover or "binding" before attachment to the inner case.

My bank comprises a box or case 2 of thin metal having a cover 3 hinged to the case by means of tongues 4 extending thru slots in the wall thereof. The tongues are bent alternately in opposite directions as shown to pivotally connect the case portions together. The general proportions of the covered case are those of a small book. A lock 6 operated by a suitable key is provided for locking the cover in the closed position, and the downwardly extending tongues 4 resiliently pressing against the rear wall provide means for lifting the cover a small amount when the bank is unlocked. A plate 7, preferably of finished metal surrounds the three edges of the bank corresponding to

the edges of the pages, and the cover when closed lies within this plate. An aperture 8 is provided for the insertion of coins. In forming the aperture, tongues 9 are pressed inwardly. These tongues are afterwards bent, during the assembling of the parts, to retain the hood 11, between which and the side of the box the plate 12 is disposed. The plate 12 and the hood are each provided with apertures alined with the coin slot 8, and convergent spring fingers 13 are formed on the plate, and extend inwardly from both sides, so that a coin pushed thru the slot must pass between them. The fingers 13 thus constitute guards to prevent the extraction of coins thru the slot.

The covering 16 of the bank is preferably formed of leather or other desired book binding material and is mounted on stiffening boards 17 preferably of thin sheet metal. On the inside the metal is lined with a layer 18 of paper, and the leather is turned over the edges and adhesively secured to the paper as shown, for example in Fig. 6. The stiffening boards are formed with tongues 19 pressed outwardly from the body of the board, and these tongues project thru the inner paper lining 18 at right angles with the plane of the board as clearly shown in Fig. 8. The cover and opposite side of the case are provided with slots 21 so placed as to be engageable by the tongues 19, when the binding is applied. With the tongues all engaged in the slots, the tongues are bent over on the inside of the case thus securely fastening the covering or binding in place. When the cover is worn or for any other reason a new cover is wanted, the old one is readily detached by bending back the tongues, and a new one applied.

Corner protective pieces 22 preferably of metal are provided on the covering, since the corners naturally receive the most wear. These corners are bent from strips as shown in Fig. 5 and are preferably provided with short studs 23 which bed in the inturned margin of the binding and paper lining and prevent disengagement of the corners. The ends of the back are also similarly protected by metallic plates 24, which, with the corner pieces are applied prior to the assembling of the covering on the inner case.

It will readily be appreciated that with the structure set forth, the "binding" of the "book" may be easily detached when worn, and a new one applied. This is of im-

portance, where the banks are loaned to depositors by financial institutions. The metallic parts are capable of long use and comprise the chief cost of the device. The 6 covers may bear the individual names of depositors. Hence it is desirable with the re-issue of a bank after its return by a former user, to attach a new cover, and with my device this may be done at small cost.

10 I claim:

1. A book form savings bank comprising a case simulating the proportions of a book, and an envelope covering simulating the binding of the book detachably interlocked with said case.

15 2. A savings bank comprising a case formed with slots in the sides thereof, and an envelope covering for said case having tongues disposed thereon to be engaged in said slots whereby the covering is retained on the case.

20 3. A book form savings bank comprising a case simulating the proportions of a book, an envelope covering on said case simulating the binding of a book and detachably interlocked with said case, and metallic plates disposed on the corners of said coverings.

25 4. A book form savings bank comprising a case simulating the proportions of a book, a covering on said case simulating the bind-

ing of a book, and metallic plates disposed on the covering at the ends of the back.

5. A book form savings bank comprising a case formed with slots in the sides thereof, 35 a covering for said case simulating the binding of a book, and stiffening boards for said cover formed with tongues for engaging said slots.

6. A book form savings bank comprising 40 a case formed with slots in the sides thereof, a covering for said case simulating the binding of a book, stiffening boards for said cover, and tongues stamped from the body of each board and adapted to extend thru 45 said slots and be bent over on the inside of said case to detachably secure the covering thereto.

7. A book form savings bank comprising 50 a case formed of hinged portions, one portion being formed with slots therein on the hinge line and the other portion being formed with two sets of tongues extending thru said slots, one set of tongues being bent away from the bottom of one of the 55 portions and the other set of tongues being bent toward said bottom, whereby the portions are pivotally connected on the hinge line.

In testimony whereof, I have hereunto set 60 my hand.

BUTLER F. GREER.

DISCLAIMER.

1,460,716.—*Butler F. Greer, San Francisco, Calif.* BOOK-FORM SAVINGS BANK. Patent dated July 3, 1923. Disclaimer filed April 27, 1929, by the patentee.

Hereby enters this disclaimer to that part of the claims in said specification which is in the following words, *to-wit*:

“1. A book form savings bank comprising a case simulating the proportions of a book, and an envelope covering simulating the binding of the book detachably interlocked with said case.

“2. A savings bank comprising a case formed with slots in the sides thereof, and an envelope covering for said case having tongues disposed thereon to be engaged in said slots whereby the covering is retained on the case.

“3. A book form savings bank comprising a case simulating the proportions of a book, an envelope covering on said case simulating the binding of a book and detachably interlocked with said case, and metallic plates disposed on the corners of said coverings.”

“5. A book form savings bank comprising a case formed with slots in the sides thereof, a covering for the said case simulating the binding of a book, and stiffening boards for said cover formed with tongues for engaging said slots.”

[*Official Gazette May 14, 1928.*]

DISCLAIMER.

1,460,716.—*Butler F. Greer*, San Francisco, Calif. BOOK-FORM SAVINGS BANK. Patent dated July 3, 1923. Disclaimer filed September 11, 1928, by the patentee.

Hereby enters this disclaimer to that part of the claims in said specification only in so far as the claims may be construed to be of broader scope than claim 6, which is in the following words, to wit:

“1. A book-form savings bank comprising a case simulating the proportions of a book, and an envelope covering simulating the binding of the book detachably interlocked with said case.

“2. A savings bank comprising a case formed with slots in the sides thereof, and an envelope covering for said case having tongues disposed thereon to be engaged in said slots whereby the covering is retained on the case.

“3. A book-form savings bank comprising a case simulating the proportions of a book, an envelope covering on said case simulating the binding of a book and detachably interlocked with said case, and metallic plates disposed on the corners of said coverings.

“4. A book-form savings bank comprising a case simulating the proportions of a book, a covering on said case simulating the binding of a book, and metallic plates disposed on the covering at the ends of the back.

“5. A book-form savings bank comprising a case formed with slots in the sides thereof, a covering for the said case simulating the binding of a book, and stiffening boards for said cover formed with tongues for engaging said slots.”

“7. A book-form savings bank comprising a case formed of hinged portions, one portion being formed with slots therein on the hinge line and the other portion being formed with two sets of tongues extending through said slots, one set of tongues being bent away from the bottom of one of the portions and the other set of tongues being bent toward said bottom, whereby the portions are pivotally connected on the hinge line.”
